poration of Illinois

Application March 12, 1945, Serial No. 582,391

10 Claims. (Cl. 153—73)

1

This invention relates to a method of making corrugated metal walls.

Various methods of making corrugated walls have been suggested, but they involve extending the corrugations outwardly of the tubular blank. The corrugations are therefore of greater diameter than the diameter of the tubular blank and the metal is stretched. Due to the procedure followed, these methods generally limit the thickness of the metal and the depth of the corrugation to be formed, and they impose limitations as to size and characteristics of the finished product and the use to which it may be put.

An object of the invention is to provide a new and novel method of making a seamless corrugated tubular wall. The corrugations are formed inwardly of the tubular blank so as to be of less diameter than the diameter of the tubular blank. The operation is preferably one of folding the metal with minimum, if any, stretching, the metal being flowed by a more or less rolling or ironing action to compensate for the corrugations being of smaller diameter than the stock so as to avoid wrinkling or other undesirable disturbance of the metal and to produce a relatively uniform thickness to the wall of the finished product.

In its more specific aspects, the method includes spinning the metal by varying increments. The steps employed result preferably in a flow of the metal producing corrugations of desired depth without disturbing the metal.

In one of the variant embodiments of the invention, the method includes forming the metal into a plurality of corrugations of limited depth, but preferably with the inner portion thereof, which may include one or more inner corrugations, of greater depth than the outer portions, so that the metal of this inner portion will be formed to a greater degree at the beginning, and then the metal of the outer portions further formed, the steps including bringing all the corrugations by increments to the desired final depth without injury to the metal.

If so desired, the method may novelly include the feature of spinning the metal into a plurality of corrugations in groups substantially in continuous relation, with the inner portions of each group spun to a greater depth at the start in order initially to effect slightly greater spinning of the metal of these inner portions. The metal at the outer portions will not be thereby disturbed. The next step may then involve spinning the metal of the outer portions to the same or a different degree. Finally, all the corrugations may then be brought to the desired final depth.

2

I have found that the outer or end corrugation of one group may be utilized as a guide or anchoring means for the rollers in drawing successive groups, and hence, the metal of the outer corrugation or corrugations of each group may be held from being initially formed as much as the metal of the inner portion. Thus, the flow of the metal can be controlled, so that, when thicker metals are used, there is little, if any, danger of unevenness in the final product disturbing the grain structure or causing fracturing or cracking of the metal.

Other objects of the invention will be apparent from the following detail description when taken in connection with the accompanying drawings.

In the drawings:

Figure 1 illustrates in side view one form of the invention disclosed;

Fig. 2 is a vertical sectional view of the same;

Fig. 3 illustrates the starting blank from which the corrugated tubular wall is formed;

Fig. 4 illustrates the second step in forming the finished blank;

Fig. 5 illustrates the next step which involves spinning the circular blank into the cylindrical form shown;

Fig. 6 illustrates the bottom of this pan cut away to leave the finished seamless tubular blank for corrugating;

Fig. 7 illustrates the machine employing the rollers effecting the corrugating operations;

Fig. 8 illustrates the first step of the corrugating, which draws a plurality of corrugations of limited depth with the middle corrugation more deeply drawn;

Fig. 9 illustrates the product after the first step;

Fig. 10 illustrates the second step;

Fig. 11 illustrates the product after the second step;

Fig. 12 illustrates the third step;

Fig. 13 illustrates the product after the third step;

Fig. 14 illustrates the fourth step;

Fig. 15 illustrates the product after the fourth step;

Figs. 16 and 17 illustrate the fifth step; and

Fig. 18 illustrates the final step of sizing to effect uniformity and straightening of the corrugations.

A corrugated tubular wall 1 formed by the process disclosed herein is illustrated in Figs. 1 and 2. It may comprise any number of corrugations 2 of any desirable depth, but formed relatively deep when desired, end flanges 3 and 4

being provided for attachment of end fittings or end plates which form a part of the expandable and contractible vessel when the corrugated tubular wall is used as such, it being understood that the corrugated tubular wall may be used wherever desired, and that it is contemplated at the outset that the invention disclosed herein will produce certain novel advantages in certain installations when end flanges are included and the other novel advantages will be obtained when the end flanges are not included. The depth of the corrugations 2 appear relatively small in Figs. 1 and 2, but the diameters of the structures shown are substantial, which causes the depth of the corrugations to appear small.

The process disclosed herein has permitted forming metal from .015 to .040 thick into corrugated tubular walls, shown in Figs. 1 and 2, of more than fifteen inches in diameter with corrugations more than one-half inch deep. The forming operations will preferably reduce the thickness of the metal at the corrugations, but it will be substantially uniform without injury to the metal. I have found for example that stock of .032 inch will in certain instances be reduced to .025 inch at the walls of the corrugations and .020 at the bends of the corrugations. These figures will vary, but they illustrate that thick metal may be spun to form relatively deep corrugations and corrugated tubular walls of substantial size may be made. They also may be made stronger and have many new uses.

To make the tubular wall seamless, a piece of sheet metal shown in Fig. 3 is cut to form the circular piece 5. Piece 5 may then be spun to form a shallow pan 6, which, with the bottom 7 cut therefrom, as shown in Fig. 6, will form the tubular wall 8 to be corrugated. Bottom 7 may then comprise the circular piece 5 shown in Fig. 4 of a small size unit to be corrugated. Wall 8 is thus uniquely made without a seam, although it may be of considerable diameter and not a small tube of pipe-like dimensions. It will be understood, however, that the forming steps to be hereinafter described might be applied to corrugating small tubes of pipe-like dimensions without departing from novelty residing in employing such forming steps.

In order to spin wall 8 in small increments and by a number of operations, with the middle portion initially spun more than the outer portions, I provide a pair of rollers 10 and 11 adapted to be mounted upon rotatably driven spindles 12 and 13 adjustable toward and away from each other, say by device 14, and axially of each other by devices like 15. Roller 10 may be the upper roller and roller 11 may be the lower roller. Upper roller 10 is preferably the male die and lower roller 11 is the female die, the former having a series of annular ribs or beads, the inner being designated 16 and the outer being designated 17, which may be of smaller diameter than the inner. Lower roller 11 may have a series of grooves 18 of equal depth to receive beads 16 and 17, the number of each depending upon the number of corrugations to be formed upon each operation.

It will be observed that grooves 18 are of greater depth than beads 17, but of the same depth as bead 16. Upon the first spinning operation, tubular wall 8 is placed upon lower roller 11 and upper roller 10 is brought against the work through operation of device 14. Beads 17 of the upper roller 10 will enter outer grooves 18 of the lower roller 11, while beads 16 of the lower

roller 11 will enter grooves 20 of the upper roller 10. Bead 16 being greater in depth than beads 17 will enter the middle groove 18 of the lower roller 11 the entire depth and fold the metal to a greater extent at this middle portion than at the outer portions. This folding action is equally distributed throughout the middle portion, and consequently, the metal is not strained to disturb the grain structure to the point of fracturing or cracking the metal.

When thicker metals are employed and it is desirable to form corrugations of substantial depth, minimum folding during any one operation is desirable within practical limits of operating costs. Consequently, forming a minimum number of corrugations on the first operation may produce better results, although forming more than three corrugations, as shown in Fig. 8, may be preferred. In any event, folding the metal to a greater degree at the middle portion may be employed when it can be accomplished without injury to the metal.

The action of rollers 10 and 11 upon the metal is principally one of folding. Stretching may be eliminated if it is possible, although some stretching may occur without experiencing detrimental effects of a serious character. The seamless cylindrical wall 8 is placed upon roller 11 and beads 16 and 17 are brought downwardly thereupon so that the metal is folded inwardly with respect to the diameter of the cylindrical wall. I find that folding the outer portions to a lesser depth than the middle portion will allow the two outer folds 22 and 23 and the inner fold 24 to be formed without excess material piling up or wrinkling of the material. Inward folding of the metal eliminates the need of stretching because the material at the folds assumes a smaller diameter.

The product formed by the first operation is shown in Fig. 9. It includes the two outwardly formed folds or corrugations 25 and 26, the inwardly formed folds or corrugations 22, 23 and 24, and the unworked ends 27 and 28. This product is then lifted from lower roller 11 and repositioned thereupon to place corrugations 23 opposite the left hand outer groove 18 in roller 11 whence it is seated with a fresh portion of the wall 8 of end 28 over the middle and the right hand grooves 18. Placing corrugation 23 in the left hand groove 18 anchors the work so that during the next operation when roller 10 is brought against roller 11, as shown in Fig. 10, another group or series of folds or corrugations 29 to 32 will be formed, the product of this second operation being shown in Fig. 11. Corrugations 29 and 30 are inwardly turned while corrugations 31 and 32 are outwardly turned. Again the corrugation or corrugations representing the middle portion of this group or series is formed deeper than those of the outer portion. If a single corrugation like corrugation 29 comprises the inner portion, it will be folded deeper than corrugations 23 and 30.

When this second operation is completed, the product thus formed will have inwardly turned corrugations of alternating depths, the corrugations 24 and 29 being of greater depth than the corrugations 22, 23 and 30, the latter representing the outer portions of the two operations. At this point, it will be understood, however, that both the inner and outer portions may comprise more than a single corrugation if so desired.

The next step comprises deepening corrugation 23 to the same depth as corrugations 24 and

29. This operation is shown in Fig. 12. The lower roller 11 is removed from spindle 13 and another roller 35 is substituted. Roller 35 is substantially the same as roller 11 except for the provision of four grooves 36 instead of the three grooves 18. Grooves 36 are preferably of the same depth as grooves 18. Corrugations 24, 23, 29 and 30 are seated in these grooves and upper roller 10 is positioned so as to bring deeper bead 16 into corrugation 23 to deepen the same to the same depth as the other two middle corrugations 24 and 29. Due to the surplus material gathering at these corrugations when formed inwardly of the wall 8 so that they have a diameter smaller than the wall 8, the action of bead 16 is more or less that of rolling or ironing out the metal without stretching the same. Beads 17 entering corrugations 24 and 29 act to anchor the product during the deepening of corrugations 23.

The next step involves deepening outer corrugations 22 and 30 to the same depth as the other corrugations 24, 23 and 29, and, at the same time, further deepening all these corrugations, the amount of deepening depending upon the metal and its thickness to avoid disturbing grain structure or any injury that is apt to cause cracking or fracturing. This step may be uniquely accomplished by rollers 38 and 39 shown in Fig. 14. The operation involves first giving the corrugations a substantially V-shape cross section and extending their depth slightly. Roller 39 is provided with a groove 40 for each inwardly formed corrugation. The grooves 40 are separated by ribs 41 adapted to receive the outwardly formed corrugations 25, 26, 31 and 32. Upper roller 38 is provided with ribs 42 which are less in thickness than the width of inwardly formed corrugations 22, 24, 23, 29 and 30. As will be noted in Fig. 14, ribs 42 will narrow these corrugations at the curved ends and cause them to assume a somewhat V formation.

The product is then removed and subjected to a further operation illustrated in Figs. 16 and 17. A roller 43 provided with a rib 44 is brought against the product upon a roller 45 having two ribs 46 spaced by a groove 47 of substantially the same width as groove 40 of roller 39. Rib 44 is thicker than ribs 42 of roller 38. This thickness may bear a predetermined relation to the width of groove 47, so that, as roller 43 is brought toward roller 45, rib 44 will force the inwardly formed corrugation into groove 47 and restore it to its former shape as shown in Fig. 17. Each inwardly formed corrugation is treated as shown. Not only is the shape restored, but the depth is increased, which may be the final operation for producing the desired depth. The action upon the metal is largely rolling or ironing of the metal without stretching, although there may be a slight stretching at this point if so desired. The metal is caused to flow principally by this rolling action. The thickness of the metal will remain somewhat uniform although there may be a slight reduction at certain locations. For example, if stock of .032 inch thickness is used, it will be found that the thickness may be reduced to .020 inch at the curved portions of the inwardly formed corrugations and to .025 inch at the curved portions of the outwardly formed corrugations. The ends 27 and 28 after being spun into end flanges 3 and 4, if the same are to be provided, will have their wall thickness reduced to about .027 inch, this depending upon the extent of the operation to form these end flanges. These figures are merely illustrative and may be varied according

to the extent of the rolling action of the metal to produce the desired depth of corrugations, the kind of metal used and the thickness thereof.

To assure uniformity of the corrugations and their alignment with each other, the product may be placed upon a smooth surfaced rotating cylinder 52 and a rotating sizing roller 53 may then be brought toward the same so that beads or ribs 54 of roller 53 will enter the inwardly formed corrugations 22, 23, 24, 29 and 30, as shown in Fig. 18. The corrugations are then pressed against cylinder 52 to straighten the corrugations and to produce said uniformity.

It will be understood that the metal may be annealed after any of the operations shown in Figs. 8, 10, 12, 14 and 16 if it is deemed necessary.

To illustrate the advantages to be obtained by the invention disclosed, one example of the product that may be produced has been specifically set out by way of dimensions in the drawings. In the initial folding operation shown in Fig. 8, grooves 18 may be for instance of a depth of $\frac{3}{32}$ inch, and the middle bead 16 of roller 10 of the same size. However, outer beads 17 may be $\frac{3}{32}$ inch in depth so that the outside folds will not be as deep as the middle fold. Hence, the folding action will be slightly greater at the middle portion. The same action takes place in the formation of corrugations 29 and 30 as shown in Fig. 10, corrugation 29 being the middle fold and deeper by $\frac{1}{32}$ inch than the outside folds 22 and 30. After the step shown in Fig. 10 is completed, corrugation 23 becomes a portion of the middle portion and its depth is then increased $\frac{1}{32}$ inch by the step illustrated in Fig. 12. In other words, at this stage of the method, the middle corrugations have been folded deeper than the outside corrugations. It will be apparent that any number of steps like those illustrated in Figs. 8, 10 and 12 may be employed so that more than two series or groups of corrugations may be incorporated in the final product. Even a single series may be used. It is not necessary that only three folds be formed in the first folding operation and thereafter two adopted for the second or succeeding operation. This number may also be obviously changed.

The depth of the corrugations is then extended to $\frac{10}{32}$ inch by the step shown in Fig. 14 and to $\frac{12}{32}$ inch by the step shown in Figs. 16 and 17. Thus, the corrugations are formed by small increments and in a manner to prevent injury to the grain of the metal. The metal is rolled or compressed to prevent being placed under tension. As stated previously, there may be slight stretching of the metal present, but it is preferably held at a minimum. This reference to dimensions is not to be construed as a limitation upon the scope of the disclosure, but only as illustrative of the invention and how the metal may be gradually shaped into corrugations without injury thereto.

From the foregoing explanation, it will be apparent that certain of the steps may be used independently of the others, although the invention is directly primary to producing a product having the characteristics that will be obtained when the process in its entirety is used. For example, forming the seamless wall 8 in the manner disclosed is novel and useful. On the other hand, forming a corrugated tubular wall by the steps of Figs. 8, 10 and 12 is also novel, and it is quite obvious that outer corrugations 22 and 30 may be deepened to the same depth as inner

corrugations 23, 24 and 29 without any further deepening operation of all the corrugations.

The product produced is exceptionally novel. It may be made in larger diameters and of greater corrugation depth than heretofore. Also, heavier metals may be used to exceptional advantage. The uses of the product are greatly extended.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. The method of making a flexible corrugated metal wall which includes forming in one operation a relatively thin tubular wall into a plurality but not all of the corrugations to be formed to a depth less than a final depth, repeating the forming operation to form the remaining corrugations likewise of less depth than a final depth, certain of the intermediate corrugations being formed deeper than the outer corrugations, subjecting said corrugations to a further forming operation to deepen the same and to provide uniform depth to all, then forming the corrugations to their final depth, and sizing the corrugations to make the same relatively uniform.

2. In the manufacture of a corrugated metal tubular wall of relatively large diameter, the method of forming the metal wall into a series of corrugations which comprises forming certain of the inner corrugations more deeply than the others but not to a final depth, then forming all the corrugations to a greater but even depth, and then forming the corrugations to a still greater depth.

3. In the manufacture of a corrugated metal tubular wall, the method of forming the metal into a plurality of corrugations by first forming one group of corrugations having its outer corrugations initially formed less deep than the middle, and then forming another group of corrugations contiguous with the first group, the forming operation effecting a deeper drawing of the metal of the middle portion of the second group of corrugations than its outer end portion, then forming all the corrugations to effect a greater depth for the same, and finally, forming all the corrugations to their final depth.

4. In the manufacture of a corrugated metal tubular wall, the method of forming the metal into a plurality of corrugations by first forming one group of corrugations and then another group in continuous relation therewith, the middle portion of each group being formed to a greater depth than the outer corrugations of each group, effecting a further forming operation to secure uniform depth for all middle corrugations, effecting a further forming operation to deepen the outer corrugations to substantially the same depth as the middle corrugations, and then effecting a further forming operation of all corrugations to a still greater depth.

5. In the manufacture of a corrugated metal tubular wall, the method of forming the metal into a plurality of corrugations by first forming one group of corrugations and then another group substantially in continuous relation therewith, the middle portion of each group being formed to a greater depth than the outer corrugations

of each group, effecting a further forming operation to secure substantially the same depth for the outer corrugations as for said middle portion, and finally drawing all the corrugations to a greater depth.

6. In the manufacture of a corrugated metal tubular wall, the method of forming the metal into a plurality of corrugations by forming the corrugations in groups in substantially continuous relation with each other, the middle portion of each group being initially formed to a greater depth than the outer portion of each group, then effecting a forming of the metal to secure substantially uniform depth of all corrugations, and finally, forming all corrugations to a still greater depth without fracturing or cracking the metal.

7. In the manufacture of a corrugated metal tubular wall of a relatively large diameter, the method of forming the metal into a plurality of corrugations by forming the corrugations in groups substantially in continuous relation with each other, the middle portion of each group being initially formed to a greater depth than the outer portion of each group, then effecting a forming of the metal to secure substantially uniform depth of all corrugations, and effecting successive forming operations to deepen said corrugations still further without fracturing or cracking the metal or weakening the same at the bends of the corrugations.

8. In the manufacture of a corrugated metal tubular wall, the method of forming the metal into a plurality of corrugations in groups substantially in continuous relation with each other by a plurality of die rollers each having a number of annular ribs of predetermined depth, initially utilizing at least two of said rollers to form said groups of corrugations in continuous relation by a successive forming operation for each successive group, utilizing the end corrugation of one group as a guide and anchoring means for the rollers in making a successive forming operation, thereafter deepening the corrugations by rollers having ribs of greater depth, and continuing such use of rollers having ribs of greater depth until the metal of the corrugations is formed to a final depth without fracturing or cracking the same.

9. In the manufacture of a corrugated metal tubular wall, the method of forming the metal into a plurality of corrugations in groups substantially in continuous relation with each other by a plurality of die rollers each having a number of annular ribs of predetermined depth, initially utilizing at least two of said rollers to form said groups of corrugations in continuous relation by a successive forming operation for each successive group, utilizing the end corrugation of one group as a guide and anchoring means for the rollers in making a successive forming operation, the ribs at the middle portions of said rollers being of greater depth than the outer ribs thereof to effect a greater forming initially of the metal by the ribs at said middle portions, then forming the end corrugation of any group used as a guide and anchor to a depth equal to the ribs of said middle portions, also forming the outer ribs to a like depth, and thereafter effecting further forming of the metal of all the ribs to produce the final depth desired.

10. In the manufacture of a corrugated metal tubular wall, the method of forming the metal into a plurality of corrugations in groups substantially in continuous relation with each other by a plurality of die rollers each having a num-

ber of annular ribs of predetermined depth, initially utilizing at least two of said rollers to form said groups of corrugations in continuous relation by a successive forming operation for each successive group, utilizing the end corrugations of one group as a guide and anchoring means for the rollers in making a successive forming operation for another group, the ribs at the middle portions of said rollers being of greater depth than the outer ribs thereof to effect a greater forming initially of the metal by the ribs at said middle portions, then forming the end corrugation of any group used as a guide and anchor to a depth equal to the ribs of said middle portions, also forming the outer ribs to a like depth, and thereafter effecting further forming of the metal of all the ribs to produce the final depth desired whereby the metal is drawn to a substantially uniform thickness without fracturing or cracking

the same, and finally straightening the corrugations by a rolling operation.

FREDERICK W. GEHRER.
